(57) CLAIM

The ornamental design for a gaming machine accent panel as shown and described.

DESCRIPTION

FIG. 1 is a right perspective view of a first embodiment of a gaming machine accent panel showing our new design in a first position.

FIG. 2 is a rear perspective view of the gaming machine accent panel shown in FIG. 1.

FIG. 3 is a front view of the gaming machine accent panel shown in FIG. 1.

FIG. 4 is a rear view of the gaming machine accent panel shown in FIG. 1.

FIG. 5 is a left side view of the gaming machine accent panel shown in FIG. 1.

FIG. 6 is a right side view of the gaming machine accent panel shown in FIG. 1.

FIG. 7 is a top view of the gaming machine accent panel shown in FIG. 1.

FIG. 8 is a bottom view of the gaming machine accent panel shown in FIG. 1.

FIG. 9 is a perspective view of the gaming machine accent panel shown in FIG. 1 in a second position with environment.

FIG. 10 is a right perspective view of a second embodiment of a gaming machine accent panel showing our new design in a first position.

FIG. 11 is a rear perspective view of the gaming machine accent panel shown in FIG. 10.

FIG. 12 is a front view of the gaming machine accent panel shown in FIG. 10.

FIG. 13 is a rear view of the gaming machine accent panel shown in FIG. 10.

FIG. 14 is a left side view of the gaming machine accent panel shown in FIG. 10.

FIG. 15 is a right side view of the gaming machine accent panel shown in FIG. 10.

FIG. 16 is a top view of the gaming machine accent panel shown in FIG. 10.

FIG. 17 is a bottom view of the gaming machine accent panel shown in FIG. 10; and,

FIG. 18 is a perspective view of the gaming machine accent panel shown in FIG. 10 in a second position with environment.

The broken lines immediately adjacent to the shaded areas depict the bounds of the claimed design, while all other broken lines are directed to environment. The broken lines form no part of the claimed design.

1 Claim, 16 Drawing Sheets
